UNITED STATES PATENT OFFICE.

CLARENCE H. TAUBEL, OF RIVERSIDE, NEW JERSEY.

DESIGN FOR A STOCKING.

Application filed May 31, 1927. Serial No. 22,243. Term of patent 14 years.

To all whom it may concern:

Be it known that I, CLARENCE H. TAUBEL, a citizen of the United States, and a resident of Riverside, in the county of Burlington and State of New Jersey, have invented a new, original, and ornamental Design for a Stocking, of which the following description, in connection with the accompanying drawings, is a specification.

In the drawing:

Fig. 1 is a side elevation of a stocking embodying the design; and

Fig. 2 is an enlarged detail of the design illustrated in Fig. 1.

The design is employed at the high splice area only of the stocking, and comprises vertical stripes spaced substantially from each other, so that the body thread or color of the stocking is presented between the stripes which are of contrasting color with the body of the stocking. The said stripes are of varying height, as shown.

I claim:

The ornamental design for a stocking, as shown and described.

In testimony whereof, I have signed my name to this specification.

CLARENCE H. TAUBEL.
